UNITED STATES PATENT OFFICE.

CHARLES BERNARD WHITE, OF MANCHESTER, ENGLAND, ASSIGNOR TO JOHN LINDLEY CARR, JAMES CARR, AND EDWARD HOYLE CARR, ALL OF MANCHESTER, ENGLAND.

LOOM FOR WEAVING WARP-PILE FABRICS.

1,023,537.

Specification of Letters Patent.

Patented Apr. 16, 1912.

Application filed February 16, 1909. Serial No. 478,303.

To all whom it may concern:

Be it known that I, CHARLES BERNARD WHITE, a subject of the King of Great Britain and Ireland, and a resident of Manchester, in the county of Lancaster, England, have invented new and useful Improvements in and Relating to Looms for Weaving Warp-Pile Fabrics, of which the following is a specification.

10 This invention relates to improvements in the method of and appliances for producing warp pile or loom patterns described in the specification of prior Letters Patent No. 871382 granted to the present applicant.

15 The object of these present improvements is to so form, dispose, and operate the appliances described in the said specification as to render them easily applicable for the production of repeat spot or like designs

20 upon cloth being produced in broad looms.

The accompanying drawings illustrate appliances disposed and arranged according to my invention and having two loop forming wires on each side of each repeat.

25 Figure 1 shows a loom furnished with the improved appliances in front elevation. Fig. 2 illustrates a cross section of the bars carrying the loop forming wires, and an end elevation of the devices by which such bars

30 are operated. Fig. 3 is a view in plan of the loop forming wires for one repeat and their carriages and supports. Fig. 4 is a sectional view along the line $x-y$ of Fig. 3. Figs. 5 and 6 are views of the devices em-35 ployed for throwing the loop forming wires in or out of action.

Similar letters of reference are used to indicate similar parts where they occur in the different figures.

40 A indicates the breast beam of the loom. Above it and extending across the loom or to the desired extent across the loom are four slideable bars B B¹, C C¹ which are movable in the direction of their length 45 across the warp. These bars carry frames D D¹, and E E¹, the bars B B¹ carrying respectively frames D D¹ and the bars C C¹ carrying respectively frames E E¹. As shown in Fig. 3 the frames D D¹ are to the 50 left of the pattern F being produced in the fabric G and the frames E E¹ on the right.

These frames carry slides d d¹ and e e¹ which slides are furnished with loop forming wires d² d³ and e² e³ in the manner described and illustrated in the prior specification referred to. The different slides are provided with laterally projecting pins g, the two pins on a pair of right or left hand slides projecting to the same extent as shown in Fig. 4. A similar arrangement of frames 55 and slides is used for each repeat of the pattern across the cloth, the same two bars B B¹ carrying all the left hand frames and slides and the same two bars C C¹ carrying all the right hand frames and 60 slides. Thus all the right hand frames which are attached to the same bar move simultaneously and all the left hand frames which are attached to the same bar move together. 70

Above the breast beam is mounted a rocking shaft H furnished at suitable points in its length with arms or fingers J, one for each pair of right or left hand slides. This rocking shaft is rocked as desired from the 75 jacquard mechanism through straps or the like K attached to pulleys on an intermediate shaft.

The sliding bars B B¹ and C C¹ are operated through cams L and levers M and 80 links N. These cams are driven from the loom shaft O through suitable worm or other gearing as shown in Figs. 2 and 5 and are thrown into or out of gear by means of a suitable clutch which is actuated from the 85 jacquard. In the form illustrated the loom shaft carries a worm O¹ loosely mounted thereon.

O² is a disk fixed to the loom shaft. O³ is a further disk slideable on the shaft but 90 rotating therewith and capable of being moved longitudinally thereon by a crank lever P which is lifted by the cord P¹ from the jacquard. P² is a latch lever for supporting the crank lever P and is also operated from the jacquard through a cord P³. The disk O³ has pins O⁴ on its inner face which pass through holes in the disk O² and can engage with corresponding recesses in the face of the worm O¹. 95

100 With the different parts in the positions shown in Fig. 5 the worm O¹ is locked to

the loom shaft and rotates therewith to drive the cams L and actuate the slide bars B B¹, C C¹; when the disk O³ is moved sufficiently to the left the worm is free on the loom shaft and the cams L are not rotated.

In Fig. 3 the whole of the bars B B¹, C C¹, are shown in their extreme left hand positions, the wires e² e³ being thus shown in position for engaging with and forming loops in the pile, and the wires d² d³ being shown in a position in which they cannot engage with the design warps. It will be seen that the left hand slide pins g are in the path of their finger J while the right hand slide pins are out of the path of their finger J.

The operation is as follows:—Assume the left hand wires to be bound into the design and are now required to form further loops. The two bars B B¹ are simultaneously moved to the left and carry their frames and slides to the position shown in Fig. 3. In such position the slide pins g are in the path of the finger J and upon the motion of the rock shaft H the finger J moves both slides d d¹ to the extreme outer positions on their frames as shown by the slide d¹ in dotted lines. The wires d² d³ are now in a position to be moved to the right to enter the shed. The bar B¹ is now moved to the right by its cam and the wire d³ enters the shed and forms a loop in the warps, and occupying a position corresponding to that shown for the wires e² e³. The pin g is now out of the path of the finger J which has now returned to its illustrated position, and both wires d² d³ are beaten up by the lay Q. As the lay returns the finger J again moves and again moves the slide d and the wire d² to their extreme outward positions so that the wire d² can in turn be inserted in the shed by the movement of the bar B to the right. The slides e e¹ are similarly moved to enable their wires e² e³ to be put into or withdrawn from the shed, the only difference being that their bars C C¹ are moved to the left to put their wires in the shed and to the right to withdraw them and put the slides e and e¹ into the path of the finger J. All the corresponding wires on the left of each repeat of the design across the cloth are simultaneously operated, as are also the corresponding wires on the right of the repeats.

Figs. 5 and 6 show the cam driving clutch in action. When the clutch is to be disengaged the crank latch lever P² is moved by the pull of the cord P³ from the jacquard and its upper end moves away from underneath the lever P. This lever then falls by its weight and the clutch is disengaged. When the cams are to be again rotated the cord P¹ is pulled from the jacquard, the lever P is lifted to its illustrated position

and the end of the lever P² is returned by the spring p to again latch the lever P in its raised clutch gearing position.

The cams L have the requisite shape to move the bars B B¹ simultaneously to the left and independently to the right, and to move the bars C C¹ simultaneously to the right and independently to the left.

Instead of having two wires on each side of a repeat any other suitable number borne by a corresponding number of bars may be similarly used and operated.

The operation of the jacquard mechanism to effect the different operations described will be understood by any one acquainted with the art of weaving. Conveniently the jacquard can be prevented from operating the wires when the production of a pattern is to cease by presenting an unperforated part of a card to the needles controlling the rocking shaft and the clutch respectively. After a sufficient number of picks and when the loops which were last formed are firmly bound into the cloth the wires or those wires which are engaged with the loops in the cloth are withdrawn laterally by presenting a perforated portion of a card to the needle controlling the clutch and cam. When the wires are thus withdrawn an unperforated part of a card is again presented to the latter needle and the cams are again rendered inoperative. The stroke of the sliding bars may be varied by altering the relative lengths of the arms of the levers M by pivoting them at any one of several holes formed in their lengths. When the formation of pile loops is to be resumed perforated parts of the cards are again presented to the rocking bar and clutch or cam needles in the proper sequence.

I claim:—

1. Apparatus for repeating warp pile or loop designs in a cloth, comprising in combination in a loom a set of two sliding bars, as many sets of loop forming wires as there are repeats attached to the said two bars and disposed on like sides of repeats, a second set of two sliding bars similarly carrying further sets of loops forming wires for the other sides of repeats, appliances for simultaneously operating the bars of a set to simultaneously withdraw all their wires from their loops and for separately operating such bars to insert their wires in the shed, and appliances for simultaneously moving all the wires of a set of bars outward, substantially as described.

2. Apparatus for producing repeat warp pile or loop designs in a cloth, comprising in combination a set of sliding bars, as many sets of loop forming wires as there are repeats attached to such bars and disposed on like sides of the repeats, a second set of sliding bars similarly carrying further sets of the loop forming wires for the other sides

of the repeats, a rock shaft having fingers for moving the wires, cams and accessories for sliding the bars, a clutch for putting the cams in and out of action, and jacquard devices for operating the rock shaft and the clutch, all disposed arranged and operating substantially as described.

In witness whereof I have hereunto set my hand in the presence of two subscribing witnesses.
